(57) **CLAIM**

We claim the ornamental design for a battery operated ultra-low volume fogging and misting unit, as shown and described.

DESCRIPTION

FIG. 1 is an upper perspective view of a battery operated ultra-low volume fogging and misting unit showing our new design;

FIG. 2 is a first side view thereof;

FIG. 3 is a top view thereof;

FIG. 4 is a bottom view thereof;

FIG. 5 is a front view thereof;

FIG. 6 is a second side view thereof; and,

FIG. 7 is a rear view thereof.

The broken line showing is included for the purpose of illustrating and forms no part of the claimed design.
